UNITIZED CENTRIFUGAL REFRIGERATING MACHINE

Nathaniel B. Wales, New York, N. Y., assignor to
Industrial Patent Corporation, New York,
N. Y.

Application May 4, 1951, Serial No. 224,531

6 Claims. (Cl. 62—117.5)

1

This invention relates to a unitized hermetically-sealed centrifugal refrigeration machine using a radial multi-stage compressor wherein the alternate stages thereof are stationary and the interleaving stages revolve with the shell or unitized casing of the machine.

The stationary compression stages composed of vanes or buckets are formed on a disc journaled within the casing coincident with its axis of rotation. One segment of this disc is weighted to oppose its rotation as induced by the work of compression.

Using trichlorethylene, C_2HCl_3 , as the refrigerant in this machine, which requires only (4) pounds gauge pressure difference between a temperature of 123 deg. F. in the sump and 20 deg. F. in the vaporized to obtain a change of state, the casing of this machine of approximately sixteen (16) inches in diameter and directly connected to a standard 1725 R. P. M. motor requires a counterweight in the disc including an adequate margin of weight, totaling about fifteen (15) pounds to maintain it stationary, the compressor displacing 5.8 cubic feet of trichlorethylene gas per minute to give a refrigerating effect of approximately 500 pounds of melting ice equivalent of refrigeration per 24 hours.

The hermetical casing of this invention may be formed like a dumbbell; one end thereof cooperating to form the multi-stage radial centrifugal compressor, while the other enlarged end forms the vaporizing chamber. In the compressor end, means are provided to enhance angular velocity of the gaseous refrigerant, while in the vaporizing end, means are provided to minimize or destroy angular velocity of the gaseous refrigerant in order to obtain a liquefaction in the compressor and a vaporizing of the liquid refrigerant in the vaporizer.

The objects of this invention are as follows:

(1) A completely unitized hermetically-sealed centrifugal compression refrigeration system adapted to be rotated about its symmetrical axis whereby its rotation produces a continuous cycling refrigerating effect and sufficient windage induced by its rotation to dispense with all auxiliary blowers or circulators for supplying heated or cooled air therefrom.

(2) Means in a unitary revolving envelope to obtain an adequate degree of compression by centrifugal acceleration of the gaseous refrigerant in the compression portion of the unitized envelope without creating sufficient angular acceleration of the gases in the vaporizing portion of the envelope or, in other words, a centrifugal

field sufficient to militate against the liquid refrigerant's vaporization therein at desirable low vaporizing temperatures.

(3) A centrifugal compressor completely enclosed within a hermetical revolving envelope wherein alternate stages of centrifugal compression are produced by stationary buckets secured to and supported by an internally-positioned eccentrically-weighted element journaled coincident with the axis of rotation of the revolving envelope.

(4) Stationary duct means within a rotating centrifugal compression refrigerating machine to continuously return the liquid refrigerant accumulating by its condensation within the periphery of the rotating hermetically-sealed centrifugal compressor casing and conveying such liquid refrigerant diametrically towards the axis of rotation and then conveying it axially into an expansion nozzle in the unitary revolving vaporizing chamber.

(5) A silent, low R. P. M. unitized centrifugal refrigerating system hermetically-contained in a revolving envelope.

(6) A low-cost refrigerating system of the type specified.

(7) Other objects are implicit in the subsequent drawings and specifications.

Referring to the drawings:

Figure 1 is a side elevation partially in section of my invention.

Figure 2 is a section taken along line 2—2 in Figure 1.

Figure 3 is a modification of Figure 1.

Figure 4 is a section taken through line 5—5 in Figure 3.

Referring to the drawings, similar numerals refer to similar parts.

Numerals 1a, 1b and 1c comprise the casing or hermetical shell of the unitized refrigerating machine. The portion 1a encloses the multi-stage centrifugal compressor composed of moving blade series 13, 14 and 15 and stationary blade series 11 and 12. Portion 1b forms the connecting gas duct between portions 1a and 1c and contains a Graphitar self-lubricating sleeve 17 which forms the bearing for stationary sleeve 16 connected to disc 6 on which the stationary series of blades 11 and 12 are secured as well as supporting counterweight 23 and tube 18 through the medium of disc 6. Portion 1c is the vaporizing chamber into which stationary tube 18 and its extension 18a convey liquid refrigerant from sump 9 in portion 1a through capillary expansion valve 19 discharging liquid refrigerant 19a therein. The shell por-

tions $1a$, $1b$ and $1c$ are sustained through axial support member 4 to the shaft 3 of electric motor 2 . Motor 2 is suitably mounted on pedestal 5 .

In the portion $1a$ of the hermetical shell, three radial series of moving buckets or vanes are shown, respectively 13 , 14 and 15 , which are secured to and revolve with shell $1a$. Interposed between these buckets, see Figure 2, are the two stationary series of vanes or buckets 11 and 12 , forming thereby a multi-stage radial centrifugal compressor wherein the gas is accelerated by the first radial series of vanes 13 , causing a gaseous induction from vaporizer portion $1c$ through portion $1b$, and the gas then contacts the stationary vanes 11 , whereby it is deflected and its angular velocity partially converted into pressure and so on through the complete series of moving and stationary buckets. All of these radially-formed buckets are shown in Figure 2 as having a straight radial geometry but these buckets may have suitably curved gas inlet and discharge edges as is well known in the multi-stage compressor art.

Turning to Figure 1, the stationary disc 6 journaled by sleeve 16 on bearing 17 supports the counterweight 23 seen in Figures 1 and 2. In Figure 2 it is shown at 23 together with pipe 18 in a position as they would normally assume when the machine is not operating and at $23a$ and $18a$ respectively in a position displaced by the torque generated by the work of compression and friction when the shell $1a$, $1b$ and $1c$ are in rotation. In this operative position the liquefied refrigerant 36 , see Figure 1, partially collects in the annular sump 9 formed by the circumferentially extended portion 7 of disc 6 and by the annular lip 8 . The gaseous refrigerant as it is compressed in the compressor to its critical change-of-state pressure, which is dictated by the mean temperature of the aerated and cooled shell $1a$, in its rotation deposits liquid refrigerant also on the inner peripheral surface of shell $1a$ as shown by numeral 37 . Means are provided by scoop element 10 which is attached to the stationary rim 7 of disc 6 to deflect any predetermined residual volume of this liquefied refrigerant from the inner peripheral surface of $1a$ and discharges it through orifice 24 into annular sump 9 to make it available for transfer through pipe 18 which enters into stationary annular sump 9 , whereby the liquid refrigerant is conveyed through pipe 18 to the approximate axial center of the machine and enters expansion valve 19 and is thereby discharged at $19a$ into vaporizing chamber 22 by virtue of the pressure head existing between the comparative low pressure existing in vaporizing chamber 22 due to its evacuation by the suction of the multi-stage compressor in portion $1a$ through the open duct portion $1b$ as compared with the pressure existant in annular stationary sump 9 , which is approximately a pressure differential of four pounds gauge.

It is to be noted that the comparatively long Graphitar self-lubricating bearing 17 forms a seal between the space 38 in $1a$ and the vaporizer space 22 , but its sealing factor is largely effected by the annular bushing 50 , see Figure 2, secured to sleeve 16 , which forms a seal against the edge of graphite sleeve 17 by virtue of the pressure difference exerted axially on sleeve 16 between chamber 38 and vaporizing chamber 22 .

Suitable ducts such as 25 , 26 , 27 , 28 and 29 may surround the shell $1a$, $1b$ and $1c$ to define and direct the cold or heated air streams passing therethrough due to the windage caused by the

geometry of said revolving shell. Struts 29 in sub-atmospheric vaporizing chamber 22 serve to prevent distortion of the walls of portion $1c$ due to atmospheric pressure.

In Figures 3 and 4 a slight modification is shown of the invention as disclosed in Figures 1 and 2. In Figures 1 and 2 the pendulous counterweight 23 is shown in the compressor portion $1a$ in order to locate this weight as close to the shell-supporting bearings of motor 2 whereas in Figures 3 and 4 bearings are provided at both ends of shell portions $1a$, $1b$ and $1c$, as is seen by pedestals 30 and 31 and outboard shaft 33 secured to portion $1c$ and journaled in bearing 34 on pedestal 31 .

By the positioning of the counterweight 35 in Figure 4 in vaporizing chamber 22 , it is possible to rotate the entire shell $1a$, $1b$ and $1c$ at a higher R. P. M. to reduce the diameter of the machine for a given necessary compression ratio between chambers 38 and 22 due to the decelerative action of the stationary surface of counterweight 35 opposing angular velocity of the gases entrained by the higher rotation of chamber 22 , see arrows 39 in vaporizer 22 , Figure 4, which permits attaining low temperatures in the vaporizing chamber 22 by minimizing the centrifugal effect of the entrained gas therein and permitting an effective change-of-state of the liquid refrigerant at a lower pressure therein and hence lower temperature than would otherwise occur.

Due to the counter-flow occurring in portion $1b$, that is, the relatively cold gases leaving the vaporizing chamber 22 by the induction of the suction of the multi-stage compressor in portion $1a$ and the countercurrent of the liquid refrigerant $19a$ flowing in pipe 18 and $18a$ to expansion valve 19 , an efficient heat interchange occurs therebetween.

Operation

The operation of my invention is briefly as follows: On energizing motor 2 , shell portions $1a$, $1b$ and $1c$ are revolved by shaft 3 of motor 2 to which they are secured and supported. The bucket series 13 , 14 and 15 rotate with shell portion $1a$, to which they are secured, while the bucket series 11 and 12 remain stationary due to their securing to disc element 6 , which is pendulously counterweighted by weight 23 and journaled on Graphitar bearing 17 formed coincident with the axis of rotation of shell $1a$, $1b$ and $1c$. In this manner, the respective series of moving and stationary buckets form a multi-stage compressor which achieves the required pressure differential to liquefy the gaseous refrigerant at relatively low R. P. M. in respect to the diameter of shell portion $1a$. As the refrigerant's gas is liquefied near the outer periphery of shell $1a$, which is effectively air-cooled by its rotation, the liquid refrigerant is deposited partially in the stationary circumferential sump 9 and partially on the interior surface of shell portion $1a$ about its inner periphery. As this liquid refrigerant accumulates to a predetermined amount scoop 10 secured through the wall 7 of sump 9 formed about the outer periphery of stationary disc 6 lifts the liquid refrigerant into sump 9 through the raised lipped orifice 24 , see Figure 2, and fills the lower segment of the stationary sump 9 . A stationary pipe 18 secured to disc 6 and in open connection to the floor of sump 9 in this lower segment of sump 9 , conveys the liquid refrigerant under the pressure head

celeration of the vaporized gases therein induced by the skin friction of said revolving shell of said third portion.

6. A centrifugal compression refrigeration machine comprising a symmetrical hermetical shell, a refrigerant in said shell, journal means on which to rotate said shell about its axis of symmetry, motor-actuated means to rotate said shell, said shell divided into three portions, the first portion containing a moving stage of buckets secured to said shell to generate acceleration of the gas of said refrigerant, the third portion containing expansion means to gasify said liquid refrigerant and gaseous deceleration means whereby to offset the centrifugal field generated by the frictional contact of said gaseous refrigerant with the interior thereof, the second portion forming a communicating passage between the axes of said first and said third portions, an element in said first portion journaled in 20 said second portion and maintained stationary

by a pendulous weight, said stationary element sustaining a stage of buckets cooperating with said moving stage of buckets in said first portion to compress the gas of said refrigerant whereby to cause its liquefaction, and collection and conveyance means sustained by said stationary element to collect and convey the refrigerant liquefied in said first portion through said second portion into said expansion means in said third portion.
